UNITED STATES PATENT OFFICE.

OSCAR HOCHER, OF CLINTON, WISCONSIN.

BOTTLE FILLING AND CAPPING MACHINE.

1,049,089.

Specification of Letters Patent.

Patented Dec. 31, 1912.

Application filed March 18, 1912. Serial No. 584,504.

To all whom it may concern:

Be it known that I, OSCAR HOCHER, a citizen of the United States, and a resident of the city of Clinton, county of Rock, and 5 State of Wisconsin, have invented certain new and useful Improvements in Bottle Filling and Capping Machines, of which the following is a specification.

My invention relates to improvements in 10 bottle filling and capping machines and more specifically to improvements in that class of machines of the character mentioned which are designed especially for use in filling and capping milk and cream bottles.

15 The object of my invention is the production of a bottle filling and capping machine, as mentioned, which will be of improved construction and efficient in operation.

Other objects will appear hereinafter.

20 With these objects in view my invention consists in the combinations and arrangements of parts hereinafter described and claimed.

25 The invention will be best understood by reference to the accompanying drawings forming a part of this specification, and in which,

Figure 1 is a perspective view of a bottle filling and capping machine embodying my 30 invention, portions being shown in section in order to better illustrate the construction. Fig. 2 is an enlarged detail section of a portion of the machine showing the liquid discharge and the cap applying mechanism. Fig. 3 is a detail side elevation of one of the 35 cap magazines detached. Fig. 4 is a detail horizontal section showing one of the movable plates included in the construction in which are mounted the lower sections of the 40 liquid discharge pipes and in which are secured the cap applying plungers. Fig. 5 is a side elevation of the construction shown in Fig. 4. Fig. 6 is a fragmentary enlarged detail section taken substantially at the lower 45 end of Fig. 4. Fig. 7 is a plan view of the valves governing the liquid discharge openings in the liquid reservoir. Fig. 8 is a side elevation thereof. Fig. 9 is a side elevation of the liquid reservoir and certain of the 50 other parts adjacent thereto. Fig. 10 is an end elevation of the construction shown in Fig. 9. Fig. 11 is a plan view of the lower portion of the construction shown in Figs. 9 and 10, the supporting gear of the reservoir 55 being omitted. Fig. 12 is an end view of the

construction shown in Fig. 11, and Fig. 13 is a sectional detail of the mechanism controlling the reciprocation of one of the sliding plates shown in Figs. 11 and 12. Fig. 14 is a sectional detail of the mechanism controlling the reciprocation of the sliding plate 23 shown in Fig. 11. 60

The preferred form of construction as illustrated in the drawings comprises a bottle receptacle or support 1. The member 1 is in the form of a tray rectangular in form and supported upon legs 2. Handles 3 provided at the extremities of the receptacle, afford means for readily transporting the same. Arranged in said receptacle are four 70 baskets or boxes 4 in which the bottles 5 are arranged for filling in the manner herein-after described. The respective ends 6 of the receptacle 1 are hinged as shown in Fig. 1 in order to permit of ready removal of the 75 baskets 4, it being clear that with this provision removal of said baskets may be readily effected by sliding the same horizontally upon the bottom of said receptacle. Each basket is preferably of a size such as to 80 adapt the same to hold a predetermined number of bottles, and preferably twelve as shown in the drawing, the arrangement being such that, when the four baskets are arranged in position in the receptacle 1, there will be four rows of bottles, each row containing twelve bottles. 85

Arranged above the bottles is a reservoir 7 of rectangular form, said reservoir being 90 of a width equal substantially to the width of the receptacle 1 and of a length equal substantially to the length of one of the baskets 4. Said reservoir is supported upon a movable gear comprising the supporting legs 8 and the wheels 9. The wheels 9 engage 95 parallelly extending grooves 10 provided for the reception thereof at the upper longitudinal edges of the receptacle 1 so as to permit of free movement of the liquid reservoir from one end of said receptacle to the other, there being handles 11 provided at the ends of said reservoir to facilitate 100 moving the same as mentioned.

Provided in the bottom of reservoir 7 are 105 discharge openings 12 corresponding in number and arrangement with the bottles 5 positioned at one end of the receptacle 1, that is with the bottles contained in two of the boxes 4 provided at one end of said receptacle. The discharge openings 12 are gov- 110

erned by valves 13 which are adapted to seat therein, the valves 13 being mounted in a frame 14 so that simultaneous operation of said valves will be effected. The frame 14 5 is operated through the medium of an upwardly projecting stem 15 which projects through the cover of receptacle 7, the same being splined to said cover as shown in Fig. 9. The exteriorly upwardly projecting 10 end of the stem 15 is provided with a pin 16 which engages an inclined slot 17 provided in a sleeve 18 which incloses said end of said stem, the arrangement being such that vertical movement of said stem and 15 hence of the valves 13 connected therewith may be effected by oscillating the hand wheel 19 which is operatively connected with said sleeve. With this arrangement the simultaneous operation of all of the valves 13 in 20 order to effect discharge of the liquid from the reservoir or to stop the flow of liquid therefrom may be secured with the greatest expedition by simply oscillating or turning said hand wheel.

Arranged below the reservoir 7 and spaced therefrom is a horizontal plate 20 which is rigidly secured to the members 8 of the reservoir gear. Liquid discharge pipes 21 which connect with and depend from the 25 discharge openings 12 in the bottom of reservoir 7 communicate with openings 22 which are provided in said plate 20, as clearly shown in Figs. 2 and 11. Arranged below the plate 20 is another plate 23, the 30 longitudinal edges of said plate being slidably mounted in angular strips or bars 24 which are secured to the plate 20 at the under side thereof and at the respective longitudinal edges of said plate 20. Interposed 35 between the plates 20 and 23 is a slidable plate 25, the plate 25 being considerably thinner than the plates 20 and 23 as shown in the several figures. Sliding movement of the plate 23 may be manually effected 40 through the medium of laterally projecting handles 26 which are secured upon the under side of said plate, an upwardly projecting handle 27 provided at one extremity of the plate 25 affording means whereby manual sliding of said plate 25 may be obtained. The handles 26 are employed to move plate 23 in one direction, helical compression springs 28 being provided to move said plate in the opposite direction, that is 45 to return the same to normal position. The springs 28 are interposed between laterally projecting lugs 29 which are formed upon the shanks of the handles 26 and stops 30 which are secured upon the under sides of 50 the guide strips 24, said springs being mounted upon pins 28', the corresponding extremities of which are secured in the lugs 29, the opposite ends of said pins slidably engaging the stops 30. The amplitude of 55 sliding movement of the plate 23 is governed by nuts 31 threaded upon the pins 28' and adjustable stops 32 which are mounted for 60 slideable adjustment upon said pins, said stops and nuts being adapted to engage with the angular stops 30 before mentioned. With this arrangement it will be seen that 65 adjustment of the amplitude of movement of said plate may be effected by simply adjusting the proximity of the nuts 31 to the stops 32. A spring 33 co-operates with the plate 70 75 80 85 90 95 100 105 110 115 120 125 130 25 in the same manner as the spring 28 co-operates with the plate 23, a nut 34 and an adjustable stop 35 mounted upon the pin 33' projecting from the plate 20 and which carries the spring 33 co-operating with an angular arm 36 projecting from one end of said plate 25; and so that adjustment of the amplitude of sliding movement of said plate 25 may be secured by adjusting the relative positions of said nut 34 and stop 35. The plate 23, however, is adapted for vertical as well as horizontal movement. In order to afford vertical movement of said plate 23 the guide strips 24, as clearly shown in Figs. 4, 5 and 6, are cut away at 37 in order to 90 permit of the passage of the engaging lugs 37' which are provided at the edges of said plate for engagement with said guide strips, it being clear that with this construction depression or downward movement of the plate will be permitted when the lugs 37' are in registration with the slots 37. This registration of the lugs 37' with the slots 37 takes place only when said plate is at its forward terminal of movement and so that depression of said plate may be effected then only when said plate is in this position. The slots 37 are yieldingly closed by spring held presser members 38, the tension springs 39 co-operating therewith being interposed between 100 heads which are provided at the upper ends of said presser members and straps 40 secured upon the under sides of the guide strips 24. Stops 41 carried at the lower extremities of said presser members are adapted to engage against the under sides of the straps 40 to limit the upward movement of said presser members in order that said ends thereof shall normally be positioned flush with the upper surface of said strips 24. With this arrangement, when the plate 23 is at its upper terminal of movement, the same will not drop by gravity since the presser members 38 will engage with the lugs 37 and thereby serve to support said plate, it being required if it is desired to press said plate to exert a downward force upon the handles 26.

Carried in the plate 23 are depending tubular sections 42 which are coaxial with the discharge pipes 21, when the plate 23 is in normal position. Provided in the plate 25 are openings 43 also coaxial with said discharge pipes when said plate is in normal position, an unobstructed passage being thus

afforded for the liquid in the passage thereof to the bottles which are positioned below in the receptacle 1.

Mounted upon the plate 20 are vertically disposed cylindrical tubes 44 designed to serve as magazines for the caps or closures for the bottles 5, the lower ends of said tubes 44 being mounted in circular openings 44' provided in said plate. The magazines 44 are open at their upper ends to permit of insertion of the caps 45 therein, a weight 46 being arranged in each magazine resting upon the upper end of the plurality of caps provided therein to force the caps downwardly. A laterally projecting hand piece 47 carried by each of the weights 46 projects through a longitudinally extending slot 48 provided in the adjacent side of the magazine for effecting removal of the weight 20 when replenishing the supply of caps in the magazine. Formed in the plate 25 are circular openings 48 which are positioned for registration with the openings 44' when said plate is in normal position. The arrangement is such that, with said plate 25 in normal position, the lowermost of the caps provided in the various cap magazines will be positioned in the openings 48, and so that upon forward sliding of said plate, said 30 lowermost caps will be conveyed by said plate to tubes 42 and deposited therein. Thus, with this construction it will be seen that removal of the bottle caps and the carriage thereof for deposit upon the upper 35 ends of the bottles is effected by simply reciprocating the plate 25.

Carried at the under side of the plate 23 are depending plungers or posts 49 secured to said plate by dowels or pins 50. The 40 plungers 49 are so positioned, that when the plate 23 is at its forward terminal of movement, said plungers will be positioned directly over the bottles 5 and so that, upon depression of said plate, as above mentioned, 45 said plungers will be forced downwardly into engagement with the caps deposited upon the upper ends of said bottles in order to effect the application or the pressing into position of said caps in the bottles as will be 50 readily understood.

In the operation of the device, the same is first positioned over the bottles provided at one end of the receptacle 1. The hand wheel 19 is then moved to elevate the valves 13 and 55 permit of the discharge of the liquid from the reservoir into the bottles positioned under said reservoir. When the bottles are filled the hand wheel is turned to lower the valves 13 and thereby stop the flow of 60 liquid from the reservoir. The plate 25 is then drawn forward to carry the caps from the cap magazines and deposit the same upon the upper ends of the bottles. This being done the plate 25 is released, the 65 same being returned to normal position by

the spring which co-operates therewith. The plate 23 is then moved forwardly to its forward terminal of movement and then depressed, such operation effecting the application of the bottle caps or closures in the manner before described, thus completing the filling and capping of the bottles at one end of the receptacle 1. The reservoir is then moved to position over the bottles at the other end of the machine and the operation just described repeated, the set of bottles first filled being removed and new ones arranged in their position during the filling of the second set, and vice versa. With this arrangement it will be seen that the bottles may be filled with great expedition and with little expenditure of labor. The device is of durable and economical construction, and is of high efficiency in operation.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. A bottle filling and capping machine comprising a bottle receptacle; a movable liquid reservoir; discharge pipes depending from said reservoir adapted to register with the upper ends of bottles arranged in said receptacle; simultaneously operable valves governing said pipes; a guide plate arranged below and movable with said reservoir, the lower ends of said discharge pipes registering with openings in said plate; a second plate slidably mounted at the under side of said guide plate, there being openings in said second plate registerable with the lower ends of said discharge pipes; cap magazines carried upon said first mentioned plate, the lower ends of said magazines registering with openings provided in said plate; a third plate interposed and slidably mounted between said first and second mentioned plates, there being openings in said third mentioned plate registerable with the lower ends of said discharge pipes, sliding movement of said third mentioned plate effecting removal of the caps singly from said cap magazines and the carriage thereof to said openings in said second mentioned plate; and means for applying the caps to the bottles, substantially as described.

2. A bottle filling and capping machine comprising a bottle receptacle; a movable liquid reservoir; discharge pipes depending from said reservoir adapted to register with the upper ends of bottles arranged in said

receptacles; simultaneously operable valves governing said pipes; a guide plate arranged below and movable with said reservoir, the lower ends of said discharge pipes 5 registering with openings in said plate; a second plate slidably mounted at the under side of said guide plate, there being openings in said second plate registerable with the lower ends of said discharge pipes; cap magazines carried upon said first mentioned plate, the lower ends of said magazines 10 registering with openings provided in said plate; a third plate interposed and slidably mounted between said first and second mentioned plates, there being openings in said third mentioned plate registerable with the lower ends of said discharge pipes, sliding movement of said third mentioned plate effecting removal of the caps singly from 15 said cap magazines and the carriage thereof to said openings in said second mentioned plate; and plungers for engaging the caps to apply the same to the bottles, substantially as described.

25 3. A bottle filling and capping machine comprising a bottle receptacle; a movable liquid reservoir; discharge pipes depending from said reservoir adapted to register with the upper ends of bottles arranged in said 30 receptacle; simultaneously operable valves governing said pipes; a guide plate arranged below and movable with said reservoir, the lower ends of said discharge pipes registering with openings in said plate; a second plate slidably mounted at the under side of said guide plate, there being openings in said second plate registerable with the lower ends of said discharge pipes; cap magazines carried upon said first mentioned plate, the lower ends of said magazines 35 registering with openings provided in said plate; a third plate interposed and slidably mounted between said first and second mentioned plates, there being openings in said 40 third mentioned plate registerable with the lower ends of said discharge pipes, sliding movement of said third mentioned plate effecting removal of the caps singly from 45 said cap magazines and the carriage thereof to said openings in said second mentioned plate; and depending plungers carried by said second mentioned plate adapted to be 50 brought to register with the bottles by sliding of said plate, said plate when said plungers are in registration with the bottles being free for depression to effect engagement of said plungers with the caps for applying the same to the bottles, substantially as described.

55 4. A bottle filling and capping machine comprising a bottle receptacle; a movable liquid reservoir; discharge pipes depending from said reservoir adapted to register with the upper ends of bottles arranged in said 60 receptacle; simultaneously operable valves governing said pipes; a guide plate arranged below and movable with said reservoir, the lower ends of said discharge pipes

registering with openings in said plate; a second plate slidably mounted at the under side of said guide plate, there being openings in said second plate registerable with the lower ends of said discharge pipes; cap magazines carried upon said first mentioned plate, the lower ends of said magazines 65 registering with openings provided in said plate; a third plate interposed and slidably mounted between said first and second mentioned plates, there being openings in said third mentioned plate registerable with the lower ends of said discharge pipes, sliding movement of said third mentioned plate effecting removal of the caps singly from 70 said cap magazines and the carriage thereof to said openings in said second mentioned plate; and plungers carried by said second mentioned plate adapted to engage the caps to apply the same to the bottles, substantially as described.

5. A bottle filling and capping machine 85 comprising a bottle receptacle; a movable liquid reservoir; discharge pipes depending from said reservoir adapted to register with the upper ends of bottles arranged in said receptacle; simultaneously operable valves 90 governing said pipes; a guide plate arranged below and movable with said reservoir, the lower ends of said discharge pipes registering with openings in said plate; a second plate slidably mounted at the under side 95 of said guide plate, there being openings in said second plate registerable with the lower ends of said discharge pipes; cap magazines carried upon said first mentioned plate, the lower ends of said magazines 100 registering with openings provided in said plate; a third plate interposed and slidably mounted between said first and second mentioned plates, there being openings in said third mentioned plate registerable with the lower ends of said discharge pipes, sliding movement of said third mentioned plate effecting removal of the caps singly from 105 said cap magazines and the carriage thereof to said openings in said second mentioned plate; and depending plungers carried by said second mentioned plate adapted to be 110 brought to register with the bottles by sliding of said plate, said plate when said plungers are in registration with the bottles being free for depression to effect engagement of said plungers with the caps for applying the same to the bottles, substantially as described.

In testimony whereof I have signed my name to this specification in the presence of two subscribing witnesses.

OSCAR HOCHER.
